COMPACT

Israel Bloom, New York, N. Y.

Application April 10, 1936, Serial No. 73,669

2 Claims. (Cl. 132—82)

This invention relates to compacts for face powder, rouge and the like.

Special objects of the invention are to provide a simple, attractive and entirely practical form of compact, which will hold an ample supply of powder in a cubical form adapted to leave room in a small case for a full thickness powder puff and which will keep the powder in a proper loose condition and will deliver the same to the puff, held at the outside of the case, in amounts exactly as required and without wasting or scattering the powder.

Other objects and the novel features of construction, combinations and relations of parts by which the objects are attained are set forth in the following specification, illustrated in the accompanying drawing and broadly covered in the claims.

The drawing accompanying and forming part of the specification illustrates a practical embodiment of the invention, but it will be appreciated that changes and modifications may be made as regards this particular illustration, all within the true intent and broad scope of the invention.

Fig. 1 is a broken part sectional front view of the open compact.

Fig. 2 is a broken side and part sectional view as on substantially the plane of line 2—2 of Fig. 1.

Fig. 3 is a bottom view of the article.

Fig. 4 is an enlarged cross-sectional view as on substantially the plane of line 4—4 of Fig. 1.

Fig. 5 is an enlarged broken sectional detail of the lower portion of the case, powder container and agitator with the cover slide in closed position.

Fig. 6 is a similar view showing the cover slide withdrawn to uncover the powder discharge openings.

The case is designated 1, and is shown as having a hinged front cover 8, carrying a mirror 9, at the underside of the same.

The bottom of the case is shown as having a powder discharge opening 10, controlled by a cover 11, sliding through a guide slot 12, in the adjoining side wall of the case.

Within the case, above the bottom powder discharge outlet is a powder chamber, here shown as a separately formed box 13, of a depth substantially equal to the full available depth of the case and of elongated shape, nearly the full height of the case. This powder box is shown confined in the lower corner portion and against the right hand side of the case by a spring holding catch 14, extending from the back wall of the

case and engaging over the upper end of the powder box.

A built-in rouge compartment is shown at 15, occupying the other corner and lower portion of the box, the same providing a means for confining the removable powder box in its particular corner.

This particular arrangement described leaves a full depth space at 16, at the left hand side of the box above the rouge compartment 15, for a full thickness powder puff 17. The latter is shown as occupying this full depth space, guided and held at the bottom by a flange 18, projecting up from the rouge compartment and as extending at the top up into the upper rounded end of the case beneath the cover hinge 19.

For preventing caking of the powder and for effecting positive discharge of the same, there is provided in the illustration, agitating and feeding mechanism in the form of a rod 20, extending through the top of the powder box to a bearing 21, in the bottom of the box, said rod carrying a powder propelling blade or blades 22, operating over the discharge openings 23, in the bottom of the box and the entire rod assembly being yieldingly forced downwardly in this position by a coiled spring 24, about the rod, engaged with the powder expelling paddle at the bottom and engaging the upper wall of the box as an abutment at the top. A handle or thumb turn 25, on the upper exposed end of the rod provides a convenient means by which this agitator and powder expelling device can be turned.

The powder box has a suitable cover 26, preferably in the top of the box as indicated, so that it may be opened and the box be filled with fresh powder without removing the box from the case. The rouge compartment is shown as similarly equipped with an easily opened cover 27, providing access to the rouge puff and powder.

The bottom of the case is indicated as having a turned in flange 28, at the front edge of the same forming a guide for the slide and to prevent the slide being accidentally withdrawn from the guideway so provided, cooperating limit stops 45 may be provided, such as the downward projection 29, Fig. 6, on the bottom of the powder box for cooperation with a recess 30, in the slide. A second recess 31, in the slide is positioned to cooperate with the detent 29, in the closed position of the slide, Fig. 5, to yieldingly retain the slide in this position. The lower end of the agitator rod 20, is shown in Fig. 5 as projecting sufficiently to enter the first recess 30, for yieldingly retaining the slide in the closed relation.

When the main cover is opened as in Figs. 1 and 2, the powder puff 17, may be removed and held below the powder discharge opening in the bottom of the box. Then when the cover 5 slide is pulled out and the thumb knob is turned any desired amount of powder will be sifted or discharged onto the puff. In this feeding operation, the powder in the box will be agitated and any caking tendency overcome. This agitation is 10 substantially the full length of the box, since the spring as well as the powder propelling paddle has an agitating effect on the powder. As the discharge is to the outside, no loose powder is released in the case and the case can thus always 15 be kept neat and clean. Only as much powder as is actually required need be discharged at any time, so the device is economical in the use of powder. The deep space alongside the elongated powder box provides room for a fluffy full thickness form 20 of powder puff and because of the agitating effect, the powder can be kept in a full depth form of powder box, such as indicated. The cover 26, extending as it does substantially the full length of the powder box, enables the complete contents 25 to be readily inspected at any time, or if desired, to be fully removed and be replaced with fresh material. The spring mounting of the agitating shaft permits this shaft to be bodily lifted by the thumb knob 25, for purposes of agitation or 30 breaking up any material that may have caked. The removability of this powder box enables different boxes of powder to be quickly substituted in the same case. The spring 24 holds the powder discharging shaft in the position in which it 35 is left, preventing it from shaking loosely around and exerting a powder discharging tendency, with movements of the case.

What is claimed is:

1. A powder compact comprising a case having a bottom wall with a discharge opening therein and a side wall with a guide slot directly above said bottom wall, a slide operating in said 5 guide slot to cover and uncover said bottom opening, a powder compartment in the said case above said slide and provided with a discharge opening in line with the discharge opening in the case, an agitating and powder discharge member operable in said powder compartment above the discharge opening therein and provided with an operating member at the outside of said compartment, said agitating and discharge member including a shaft element projecting through the 10 lower end of the powder compartment into the plane of said cover slide and said cover slide having a depression for receiving said projecting end of the shaft element.

2. A powder compact comprising a flat shallow 20 case having a bottom wall with a discharge opening therein, a closure slide operating over said bottom opening, a powder compartment in said case above said slide and arranged to discharge through said discharge opening in the case, an 25 agitating and powder discharging member operable in said powder compartment above said discharge opening and provided with an operating member at the outside of said powder compartment, said agitating and discharge member including a shaft element projecting through the 30 lower end of the powder compartment into position for engagement with said cover slide and a spring yieldingly thrusting said shaft element into holding engagement with said cover slide. 35
